SWIMMER'S PADDLE WHEEL

Robert A. Noe, 8543 Remmet Ave., Canoga Park, Calif.

Filed June 7, 1960, Ser. No. 60,865

Term of patent 3½ years

(Cl. D71—1)

FIG. 1 is an end elevational view of a swimmer's paddle wheel showing my new design.

FIG. 2 is a side elevational view with a portion in cross-section, to clarify configurational details.

FIGS. 3 and 4 are cross-sectional views as taken on the respective lines 3—3 and 4—4 of FIG. 2.

The end not shown is the same as the end shown in FIG. 1.

I claim:

The ornamental design for a swimmer's paddle wheel, substantially as shown and described.
